UNITED STATES PATENT OFFICE.

CHARLES E. SCRIBNER, OF JERICHO, VERMONT, ASSIGNOR TO WESTERN ELECTRIC COMPANY, OF CHICAGO, ILLINOIS, A CORPORATION OF ILLINOIS.

MEASURED-SERVICE SYSTEM OF TELEPHONE-EXCHANGES.

No. 825,424.

Specification of Letters Patent.

Patented July 10, 1906.

Original application filed February 23, 1904, Serial No. 194,801. Divided and this application filed February 6, 1906, Serial No. 244,355.

To all whom it may concern:

Be it known that I, CHARLES E. SCRIBNER, a citizen of the United States, residing at Jericho, in the county of Chittenden and State of Vermont, have invented a certain new and useful Improvement in Measured-Service Systems of Telephone-Exchanges, of which the following is a full, clear, concise, and exact description.

10 My invention relates to measured-service telephone-exchange systems; and its object is in general to provide an improved organization of circuits and apparatus whereby a record may be made of each call from a subscriber's station which is answered and the desired connection established at the central office.

15 The accompanying drawings illustrate a measured-service system constructed and 20 organized in accordance with my invention, and I will describe the same particularly by reference to said drawings, reserving for the appended claims a statement of the parts, improvements, or combinations considered 25 to be novel.

20 In the drawings, Figure 1 is a diagram illustrating by means of conventional symbols the apparatus and circuits of a telephone-line extending from a subscriber's station to a central office of a telephone-exchange. Fig. 2 is a plan view of the service-meter which is provided at the subscriber's station with the containing-case in section, and Fig. 3 is a vertical sectional view of the 35 service-meter on line 33 of Fig. 2.

The same characters of reference are used to designate the same parts wherever they are shown.

30 Referring to Fig. 1, the telephone-line extends in two limbs or line conductors 4 5 from the subscriber's apparatus S to the central switchboard C, where it is provided with the usual spring-jack terminals a a. One pole of the central battery b is connected to earth, and the other or free pole is connected to the limb 4 of the telephone-line through the winding of the line-relay c and the contacts of the cut-off relay d. The other limb 5 of the telephone-line is normally open at the 45 central office. The line-relay c controls a line signal-lamp c' in a local circuit. A portion of the usual operator's plug-circuit by

which connection is made with the line is illustrated. The tip and ring contacts of the plug form the terminals of link conductors 6 55 7, respectively, which are brought into connection with the conductors 5 4, respectively, when the operator's plug p is inserted in the spring-jack of the telephone-line. At the same time the cut-off relay is excited by current in a local circuit 8 in accordance with the usual practice. The operator's supervisory relay e is included in the link conductor 6 between the grounded pole of the battery and the tip of the plug. This supervisory relay controls a supervisory lamp e', as usual. The plug-circuit shown is of the type which is adapted to be used in telephone-exchange systems having coin-collectors at the subscribers' stations and is therefore provided with two keys f and g, by which the operator is enabled to actuate the mechanism of the subscriber's toll device. The key f is adapted when actuated to break the continuity of conductors 6 7 and connect 70 both the ends thereof leading to the plug p with the free pole of a grounded generator G. Similarly the key g when actuated is adapted to break the continuity of the conductors 6 7 and to connect the end of conductor 7 75 only to the free pole of a grounded generator G', the conductor 6 being simply opened. In practice for systems where coin-collectors as well as service-meters are employed the free pole of one of the generators will be positive, 80 while the free pole of the other generator will be negative; but this is not necessary for the operation of the service-meter herein described.

85 The subscriber's station is equipped with 90 the usual telephone transmitting and receiving apparatus, with a telephone-switch h controlling the circuits thereof, and in addition there is provided the service-meter k, the mechanism of which is shown in detail in 95 Figs. 2 and 3. The register or counting train l of the service-meter shown, which is the type which I prefer to employ in carrying out my invention, is provided with a driving ratchet-wheel r, which is arranged to be actuated by 100 a pawl o, carried by the armature m' of the magnet m. The armature m' may be termed a "two-step" armature—that is to say, its attractive movement toward the magnet-

core is divided into two steps or stages. A contact-spring s is arranged to be engaged by the armature when the same is partially attracted, so that the further attractive movement of the armature will be opposed by the tension of said spring. The initial attractive movement may be opposed simply by the weight of the armature. The pawl o is arranged to engage the ratchet-wheel r only during the final attractive movement of the armature, the initial movement being completed without advancing the counting-train. A manual switch-key t , which may control the connection of the service-meter magnet, is associated with said magnet. This switch-key is adapted to be set manually, but is arranged to be released in the initial attractive movement of the armature m' simultaneously with or shortly after the engagement of the armature with the contact-spring s . The manual switch may consist of a plunger t' , arranged to be operated manually against the tension of a coil-spring t^2 , and the armature m' may carry a detent m^2 , which is adapted to engage a notch or offset of the plunger to latch the same in its actuated position. The pawl m^2 normally rests upon a piece of insulating material t^3 , carried by the plunger; but when the plunger is depressed the pawl m^2 comes into electrical contact with the metallic portion thereof at the notch or offset. The contact thus made serves to complete the connection of a branch 9 from conductor 4 to ground, said branch including the magnet m , the plunger t being connected with said conductor and the magnet being connected between the armature m' and ground. The armature m' in its initial attractive movement makes contact with the spring s , which is connected with the other limb 5 of the telephone-line and at the same time or shortly after the switch-key is released, so that the connection of the magnet is thus transferred from one line conductor 4 to the other line conductor 5 . If the armature goes on and takes the second step to complete its attractive movement, the counting-train l also will be advanced by the pawl engaging the ratchet-wheel r . The magnet m is wound to respond to currents from the generators $G G'$, but is unresponsive to current from the battery b of lower electromotive force. It should be stated that while for convenience of illustration two batteries (marked b) are shown in the drawings it is understood, of course, that these may be one and the same battery, in accordance with the usual practice.

The service-meter above described forms no part of the present application, but constitutes the subject-matter of my application, Serial No. 194,801, filed February 23, 1904, of which this application is a division.

The operation of the system is very similar to the operation of the system where coin-

collectors are employed—such, for example, as the system of Patent No. 665,874, issued January 15, 1901, to A. M. Bullard. Indeed, the working of the system, from the central-office operator's standpoint, is identical.

In exchanges where the number of calls from a given station determine the amount to be paid by the subscriber for telephone service the system may be organized upon either of two plans: the subscriber may pay for each call as he makes it by actually depositing a coin in the coin-collector, or in place of the coin-collector each call may be recorded upon a register or meter and payment made in a lump sum at the end of a given time for the number of calls recorded. The subscriber should of course be charged for service only when the connection called for is actually obtained, and in the system of the Bullard patent before referred to the coin-collector receives the coin provisionally, and the operator may by pressing the proper one of two keys bring about the actuation of the mechanism to return the coin to the subscriber or deposit it in the cash-box, according to the circumstances.

It is sometimes desirable that an exchange be equipped partially with call-recording devices and partially with coin-collectors, as subscribers may prefer. It may be that a party-line will have some of its substations equipped with coin-collectors, while other substations of the same line will have service-meters instead. Lines of such differing character are frequently grouped together indiscriminately at the central-office switchboard, and the operator, who must do the work of establishing and taking down connection almost mechanically, should not be burdened with the mental effort of distinguishing between lines having different classes of toll devices. It is an especial advantage of the service-meter apparatus of the present invention that it may be used in systems where coin-collectors are also employed, such as the system of the Bullard patent, without requiring any different apparatus at the central office or any different action by the operator.

The call is transmitted to the central office in the Bullard system by the subscriber depositing a coin in the toll-box. In the present system the call is transmitted by the subscriber actuating his manual switch-key t . The effect in either case is to cause the display of a line-signal at the central office, to which the operator responds by plugging into the spring-jack of the calling-line. The operation of the toll device is then determined by two keys in the operator's plug-circuit. If the desired connection is obtained, the "charge-key" is depressed, which in the case of the coin-collector causes the coin to be deposited in the cash-box and in the case of the service-meter causes the call to be re-

corded upon a register. If for any reason no charge is to be made, as where the desired connection cannot be established, the operator actuates the release-key, which in the case of the coin-collector causes the coin to be returned to the subscriber and in case of the service-meter causes the mechanism to be restored without actuating the register.

To describe the operation of the system of this invention more in detail it will be seen that depressing the switch-key *t* at the subscriber's station will complete a branch circuit 9 to earth from limb 4 of the telephone-line. A circuit is thus completed from the central battery *b*, through the line-relay *c* and over conductors 4 and 9, to earth, whereby the line-relay is excited and causes the display of the line signal-lamp *c'*. The magnet *m* of the service-meter, although included in this circuit, does not respond to current from the battery *b*. The switch-key *t* being once depressed is latched in its actuated position by the pawl *m'*, carried by the armature *m'* of the magnet. The operator answers the call by plugging into the spring-jack *a* of the line, as usual, and at the proper time, which is preferably after the "disconnected signal" is received at the end of the conversation, depresses one or the other of the keys *f* *g*, according to circumstances. If no charge is to be made, the key *g* will be depressed, which will cause the armature of the subscriber's service-meter magnet to take only the initial step of its attractive movement, releasing the switch *t*, but not actuating the registering-train. If a charge is to be entered, the key *f* will be depressed, and this will bring about a complete attractive movement of the armature *m'* instead of the mere half-step and the registering-train *l* will be advanced to record the connection, the switch *t* being also released. The control of the keys *f* *g* over the subscriber's service-meter is as follows: The key *g* applies current from generator *G'* to the limb 4 of the line, and this current flows to earth through the branch 9, containing the magnet *m*, said branch being closed by the contact between the pawl *m'* and the plunger *t'* of the switch. The magnet will therefore be excited; but the armature in taking the first step in its attractive movement withdraws the detent *m'* from engagement with the offset on the plunger, whereby the plunger is released and returned to its normal position by spring *t'*, the connection of the magnet with conductor 4 being thus broken. The armature is now in contact with spring *s*, and the connection of the magnet *m* is thus transferred to the other side of the telephone-line; but current having been applied by key *g* to the limb 4 only the magnet *m* is no longer energized, but permits its armature *m'* to drop back before the pawl *s* has advanced the registering-train. When the key *f* is depressed, current from the gen-

erator *G* is applied to both conductors 4 5, so that, although the first step in the movement of the magnet-armature breaks the connection of the magnet with conductor 4, the magnet will receive current from conductor 5 70 by way of contact-spring *s*. Under these conditions the armature *m'* will complete its attractive movement and advance the registering-train by means of the pawl *o* and the ratchet-wheel *r*. It will thus be seen that the magnet is adapted to be connected progressively with different actuating-circuits by switching mechanism controlled by its own armature and that a movement of said armature through one or more steps may be 80 brought about by applying current to one or more of said actuating-circuits.

I claim—

1. The combination with an electromagnet and an armature therefor, of two branch circuits for said magnet, a switch adapted to connect the magnet with one branch, switch mechanism adapted in a partial attractive movement of said armature to transfer the connection of the magnet to the second 90 branch, and means at a distant point for applying current to the first branch alone, or to both branches, whereby the extent of movement of said armature is determined.

2. The combination with a telephone-line 95 extending from a substation to a central office, of a service-meter at the substation, an electromagnet therefor, a plurality of circuits for said magnet, a source of current at the central office, means at the central office for connecting said source of current with one or more of said circuits, switch mechanism adapted to connect said actuating-circuits progressively with the electromagnet, and an armature for said magnet controlling said 100 switching mechanism.

3. In an electromagnetic step-by-step device, the combination with an electromagnet, of a plurality of actuating-circuits therefor, switch mechanism adapted progressively to connect said actuating-circuits with the electromagnet, an armature for said electromagnet controlling said switch mechanism, a source of current, means adapted to apply said source to one circuit to cause a partial 110 attractive movement of said armature, and means for applying said source to said plurality of circuits to cause increased attractive movement of said armature.

4. The combination with a telephone-line 120 extending in two limbs 4, 5, from a substation to a central office, of a source of current and a signal instrument normally connected at the central office with one limb 4, an electromagnetic service-meter at the substation 125 having a manual switch-key associated therewith adapted to complete a circuit for said source of current through said limb 4, to cause the operation of said signal instrument, a detent adapted to latch said switch-key in 130

its actuated position, said detent being moved to release said switch-key in the response of the service-meter magnet, and means controlled at the central office for exciting said 5 service-meter magnet.

5. The combination with a telephone-line extending in two limbs 4, 5, from a substation to a central office, of a service-meter at the substation comprising a registering-train, an 10 electromagnet and an armature therefor having a pawl adapted to advance said registering-train by a complete attractive movement of said armature, the initial attractive movement being independent of said registering- 15 train, a manually-closed switch controlling a circuit through the service-meter magnet, including one limb 4 of the line, said circuit including a source of current and a signal instrument, a switch-contact closed in the initial 20 movement of said armature adapted to control a circuit through said magnet from the other limb 5 of the telephone-line, a latch for the manual switch released in the initial 25 movement of said armature, and means at the central office for applying current suitable for actuating said magnet from a grounded source to the limb 4 or to both limbs of the line, substantially as and for the purpose specified.

30. 6. The combination with a telephone-circuit having two limbs 4, 5, and an electromagnetic service-meter comprising an electromagnet, a two-step armature therefor, and a registering-train actuated in the final 35 step or movement of said armature, a manual switch-key adapted when actuated to connect the service-meter magnet with the limb 4 of the telephone-circuit, a relay-contact closed by said armature in the initial movement thereof, adapted to connect the magnet 40 with the other limb 5 of the circuit, a detent adapted to latch said switch-key in its actuated position, said detent being moved to release said key by the initial movement of said 45 armature, a source of current adapted to excite said magnet, and switching means for applying said current alternately to the limb 4 or to both limbs 4, 5, substantially as and for the purpose described.

50. 7. The combination with a telephone-line

extending from a substation to a central office, of a battery at the central office connected with one limb of said line, the other limb being open, a signal-controlling magnet in the path of current from said source, a 55 service-meter at the substation, a magnet therefor included in a ground branch from the armature thereof, a contact for said magnet connected with the open limb of the line, and adapted to be engaged by said armature 60 when partially attracted, a key connected with the battery side of the line adapted when operated to complete a circuit from said battery including the signal-controlling magnet and the service-meter magnet, said last-mentioned magnet being unresponsive to current from said battery, a detent carried by the armature of said magnet adapted to hold said switch-key in its operative position, link conductors at the central office, a connection- 70 switch for uniting the same with the line, a source of special current, and a key adapted when actuated to connect said source with both link conductors, and thereby apply current to both limbs of the line; whereby the 75 service-meter magnet is energized to effect a registration, and the said detent is withdrawn to release said switch-key.

8. In a service-meter the combination with an electromagnet, of an armature therefor, two actuating-circuits for said magnet, means for connecting said magnet with one of said circuits to set the meter, a source of current, means for applying current from said source to said circuit to disconnect the magnet and reset the meter without its being operated, switching mechanism adapted in a partial attractive movement of said armature to transfer the connection of the magnet to said second circuit, and means for applying current to both circuits to effect a registration of the meter.

In witness whereof I hereunto subscribe my name this 20th day of December, A. D. 1904.

CHARLES E. SCRIBNER.
